CLAIM

The ornamental design for a nursing bottle holder, as shown and described.

DESCRIPTION

FIG. 1 is a perspective view of the nursing bottle holder of this invention.

FIG. 2 is a front elevational view thereof;

FIG. 3 is side elevational view thereof, the opposite side being a mirror image;

FIG. 4 is a rear elevational view thereof;

FIG. 5 is a top plan view thereof;

FIG. 6 is a bottom plan view thereof;

FIG. 7 is a perspective view similar to FIG. 1; however, the broken line showing of the liner and cap is for illustrative purposes only and does not constitute a part of the design;

FIG. 8 is a perspective view of the nursing bottle holder of this invention shown in another orientation;

FIG. 9 is a front elevational view thereof;

FIG. 10 is side elevational view thereof;

FIG. 11 is a rear elevational view thereof;

FIG. 12 is a top plan view thereof; and,

FIG. 13 is a bottom plan view thereof.
